UNITED STATES PATENT OFFICE.

JOSEPH ARTHUR ROUTHIER, OF MONTREAL, QUEBEC, CANADA.

PAINT-VEHICLE AND FURNITURE-POLISH.

1,017,323.

Specification of Letters Patent. Patented Feb. 13, 1912.

No Drawing.

Application filed March 3, 1911. Serial No. 612,122.

To all whom it may concern:

Be it known that I, JOSEPH ARTHUR ROUTHIER, a subject of the King of Great Britain, residing at Montreal, in the Province of Quebec, Canada, have invented certain new and useful Improvements in Paint-Vehicles and Furniture-Polishes; and I do hereby declare that the following is a full, clear, and exact description of the invention, such as will enable others skilled in the art to which it appertains to make and use the same.

The composition consists of the following ingredients, combined in the proportions stated, viz:

Benzin	1½ gallons.
Raw linseed oil	1 pint.
Brown japan	1 pint.
Beeswax	½ pound.
Sal ammoniac	2 grams.

These ingredients are to be thoroughly mingled by agitation.

In using the above named composition as a vehicle for paints, it is not necessary to use linseed oil or any other liquids which could be used in paints.

I am not aware that all of the ingredients of my composition have been used together.

Having thus fully described my invention, what I claim as new and desire to secure by Letters Patent is:

The herein described composition of matter consisting of:

Benzin	1½ gallons.	35
Raw linseed oil	1 pint,	
Brown japan	1 pint,	
Beeswax	½ pound,	
Sal ammoniac	2 grams,	40

mixed together and used as a paint vehicle and furniture polish.

J. ARTHUR ROUTHIER.

Witnesses:

ARTHUR PRÉVOST,
ANTOINE ROUTHIER.
